LLP

(57) CLAIM

The ornamental design for a pill organizer as shown and described.

DESCRIPTION

FIG. 1 is a front, left side, top perspective view of a pill organizer showing my new design;

FIG. 2 is a front, left side, bottom perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is top plan view thereof;

FIG. 8 is a bottom plan view thereof;

FIG. 9 is a front, left side, top perspective view thereof, with the lids of the pill compartments open;

FIG. 10 is a left side, rear, bottom perspective view thereof, with the lids of the pill compartments open;

FIG. 11 is a rear elevation view thereof, with the lids of the pill compartments open;

FIG. 12 is a front elevation view thereof, with the lids of the pill compartments open;

FIG. 13 is a left side elevation view thereof, with the lids of the pill compartments open;

FIG. 14 is a right side elevation view thereof, with the lids of the pill compartments open;

FIG. 15 is a top plan view thereof, with the lids of the pill compartments open;

FIG. 16 is a bottom plan view thereof, with the lids of the pill compartments open; and,

FIG. 17 is an exploded front, left side, top perspective view.

1 Claim, 17 Drawing Sheets
